UNITED STATES PATENT OFFICE.

JOSEPH S. TINDALL, OF CEDAR SPRINGS, MICHIGAN.

MOLD.

1,171,563.

Specification of Letters Patent. Patented Feb. 15, 1916.

Application filed April 11, 1914. Serial No. 831,314.

To all whom it may concern:

Be it known that I, JOSEPH S. TINDALL, a citizen of the United States of America, residing at Cedar Springs, in the county of 5 Kent and State of Michigan, have invented certain new and useful Improvements in Molds; and I do hereby declare the following to be a full, clear, and exact description of the invention, such as will enable others 10 skilled in the art to which it appertains to make and use the same.

This invention relates to improvements in molds, and more particularly to molds for forming elongated structures, such as fence 15 posts, etc., from cement or concrete, and its object is to provide a device of this character which will be simple and substantial in construction, which may be adjusted longitudinally to form structures of different 20 lengths; which may be easily and quickly assembled and disassembled for transportation or storage, and to provide the device with various novel features of construction and arrangement as hereinafter more fully 25 described and particularly pointed out in the claims, reference being had to the accompanying drawings, in which:—

Figure 1 is a plan view of a device embodying this invention; Fig. 2 is an enlarged 30 side elevation of the same, with parts broken away; Fig. 3 is an enlarged sectional elevation on the line 3—3 of Fig. 1, with parts broken away; Fig. 4 is a fragmentary perspective view; and Fig. 5 is an enlarged end 35 view of one corner of the device.

Like numbers refer to like parts in all of the figures.

The device comprises the end members 1 and 2, each of which is provided with a 40 vertical wall 3 which is slotted vertically at intervals to receive the longitudinal partitions 4, the said end members and partitions being preferably of sheet metal construction. The side members 5, which are also of sheet 45 metal, are adapted to be attached to the respective sides of the end members, and for this purpose the base portions of the respective end members are provided with hooks 9 which engage the lower edge of the respective 50 side members, and the upper edge of each side member is provided with notches 8 which receive projections 3^a at the ends of the vertical walls of the respective side members which prevent the latter from rising 55 when the device is in use. Each of the end

members is provided at each end with a retaining hook 7 pivoted to the vertical wall and adapted to enter one of the notches 8 which is wide enough to receive it, together with the extensions 3^b, and this hook engages 60 the outer surface of the side member near its upper edge and holds it securely in operative position, the lower edge being held by the hook 9.

The upper edge of each side member near 65 one end thereof is preferably provided with a plurality of notches 8, so that the end member may be adjusted and clamped opposite any one of them, whereby the space between the end members may be varied to alter the 70 length of the posts formed therebetween. The lower edge of the side members, and also the partitions 4 are recessed near their respective ends so that the side members and partitions will engage the floor on which 75 the device is placed, the recessed portions being adapted to fit over the base portions of the respective end members 2 and 3. The side members are each preferably stiffened by means of an angle bar 6 riveted to the 80 outside surface thereof and the partitions 4 are provided in one end with openings 11, in which may be inserted a hook to remove the partitions endwise from the device.

In using this device, it is assembled as 85 shown in Fig. 1 upon a level floor and the space therein divided by the partitions 4 are filled with cement or concrete, after which the said partitions, which are not attached in any way to the end members, being merely 90 supported in the vertical slots therein, may be withdrawn endwise and the side members 5 may be removed by releasing the hooks 7 and the end members 1 and 2 moved away, leaving the molded posts upon the floor to 95 dry and harden. By removing the partitions 2 longitudinally as above stated, instead of lifting them vertically, the sharp corners of the posts which are still in a soft condition, are not broken. The device when 100 disassembled may be compactly arranged for transportation, its simplicity of construction and operation and its longitudinal adjustability make it furthermore useful.

What I claim is:—

1. A fence post mold, comprising end walls and side walls, means for detachably securing said walls to each other, said end walls also having vertical slots having ends extending beyond the end walls at intervals, 110

and longitudinal partitions supported in said slots and adapted to be withdrawn longitudinally through the same.

2. A fence post mold, comprising end members having horizontal base portions and vertical walls, side members having notches in their upper edges, hooks on the bases of the end members to engage the lower edges of the respective side members, projections on the vertical walls of the end members to enter the notches in the respective side members and pivoted retaining hooks on the said walls to engage the upper edges of the respective side members.
3. A fence post mold, comprising end members having vertical walls with vertical slots at intervals therein, side walls each having a notch in its upper edge near one

end and a series of notches in its upper edge near the other end, hooks on the end members to engage the lower edges of the respective side walls, projections on the end members to enter the said notches in the side walls, pivoted retaining hooks on the end members to engage the upper edges of the respective side walls, and longitudinal partitions adapted to be supported in said vertical slots and to be withdrawn endwise therefrom.

In testimony whereof I affix my signature 30 in presence of two witnesses.

JOSEPH S. TINDALL.
